No. 848,782.

PATENTED APR. 2, 1907.

G. H. THURSTON.
ROCK AND ORE CRUSHER.
APPLICATION FILED JUNE 9, 1906.

UNITED STATES PATENT OFFICE.

GEORGE HENRY THURSTON, OF JOHANNESBURG, TRANSVAAL, ASSIGNOR
TO ALLIS-CHALMERS COMPANY, OF MILWAUKEE, WISCONSIN, A COR-
PORATION OF NEW JERSEY.

ROCK AND ORE CRUSHER.

No. 848,782.

Specification of Letters Patent.

Patented April 2, 1907.

Application filed June 9, 1906. Serial No. 321,013.

To all whom it may concern:

Be it known that I, GEORGE HENRY THURSTON, a subject of the King of Great Britain, residing at Johannesburg, in the 5 Transvaal Colony, South Africa, have invented certain new and useful Improvements in Rock and Ore Crushers, of which the following is a specification.

My invention relates particularly to that 10 class of rock and ore breakers known as "gyratory crushers," and has for its object to provide a simple, economical, and efficient crushing-head for a rock and ore breaker of this type.

15 The invention consists in the features, combinations, and details hereinafter described and claimed.

In the accompanying drawings, Figure 1 is a vertical sectional detail of the crushing-head constructed in accordance with my improvements. Fig. 2 is a plan sectional view taken on the line 2 of Fig. 1. Fig. 3 is a section of the mantle, showing the locking-lug. Fig. 4 is a section of the core, showing the 25 locking-groove. Figs. 5 and 6 are detail sectional views of other forms of crusher, illustrating the effect of the heavy wear thereon. In the art to which this invention relates it has hitherto been proposed to make the 30 crushing-head in two parts—a core portion of relatively soft metal and a mantle portion of relatively hard metal—the object being to provide a mantle which may be removed and replaced by a new mantle when the old mantle has become worn by use. In carrying out this idea it has hitherto been proposed to use a conical or frusto-conical core portion and a similarly-shaped mantle portion placed 35 over the core portion, with means for holding the mantle portion upon the core portion.

40 So far as I am aware, however, it has hitherto been proposed to locate the interlocking means between the mantle and core portion, either at the top thereof or at an intermediate point between the top and bottom. I have illustrated in Figs. 5 and 6, respectively, crushing-heads formed in this way. Both these constructions, however, are undesirable and practically useless for the following reasons: It is quite obvious that the crushing-head in these machines is subjected to enormous strains; the parts themselves are of very heavy weight, and the metal operated

upon is refractory in character. When, therefore, a chilled or hardened mantle has 55 been mounted on a core, so as to be removable therefrom, the great pressure to which the crushing-head is subjected causes a flow of the metal comprising the core and a consequent distortion of the parts, rendering the 60 operation of the machine irregular and unsatisfactory. Furthermore, large quantities of heat are developed, resulting from the energy used up in the crushing operation. This heat passing to the mantle expands the same 65 and unless provision is made against it causes it to become loose upon the core. This looseness will cause pounding of the mantle upon the core and add to the distortion already referred to. The greatest 70 amount of friction and pressure is at the lower edge of the mantle, and it is at this point, therefore, that the greatest heat is developed. Consequently in operation if the mantle is secured to the core near its top, as 75 indicated in Fig. 5, or at an intermediate point, as indicated in Fig. 6, expansion of the lower edge of the mantle will cause a separation between the mantle and core at this point, as clearly indicated in these figures. 80 The pounding and pressure above referred to will also cause the softer material of the core to flow irregularly, as indicated in these figures, causing a distortion of the crushing-head, which renders its operation uncertain 85 and unreliable. In order to provide a crushing-head in which these difficulties are obviated and in which the mantle is firmly held in position upon the core at all times and the deleterious effects above described eliminated, I have provided the following construction.

Referring to the drawings, *a* indicates the shaft of a gyratory crusher of the desired size and strength. Upon this shaft is fitted a 95 core *b* of frusto-conical shape, which may be secured to the shaft in any well-known manner, as by keys *b'*. This particular feature, however, forms no part of my present invention. Removably mounted upon the core *b* is a mantle *c*, of chilled or hardened material, preferably manganese-steel, the mantle and core being formed so as to closely fit each other, as indicated in Fig. 1. At its lower end this mantle is provided with two 100 or more inwardly-projecting locking-lugs *d*,

having oppositely-inclined upper faces d' , and upon the lower end of the core slots e are formed, having at their lower ends, which are also at the lower edge of the core, inclined 5 web-faces e' . When the locking-lugs d are brought into engagement with the slot e , the mantle may be rotated in either direction, causing an engagement of the inclined faces on the lug with the corresponding inclined 10 portions of the slots. This results in a close interlocking engagement between the mantle and the core portion, and it will be observed that the interlocking engagement is automatic in its character. The automatic interlocking is effected by the rotation of the mantle and core thereon after the mantle has been placed over the core with the key in the groove e . By rotating the head, including the core and mantle, the tendency is for the 15 key to ride upon one or the other of the inclined faces e' , depending upon the direction of rotation of the head. Thus the mantle is automatically drawn into close engagement with the core by the rotation of these parts. 20 The location of the automatic interlock at the lower edge of the core and mantle is an important feature of my invention, for by so locating the interlock I do away entirely with the objectionable features of devices used 25 suggested in the prior art. As before stated, the tendency of the mantle to expand at this point is greatest. The pressure is also greatest at this point, causing the tendency of the core portion to flow. By placing the interlock, however, at the lower edge of the core and mantle I provide a means whereby the 30

expansion of the parts at the lower edge, tending to separate the mantle from the core, is counteracted by reason of the constant automatic drawing into engagement of these 40 parts by the interlocking devices. Furthermore, should the metal tend to flow downwardly, as indicated in Figs. 5 and 6, the result is a firmer engagement of the interlocking parts, counteracting this tendency. It 45 will further be observed that the interlock is of such nature as to draw the frusto-conical mantle down upon the frusto-conical core, so that all the parts of the device are firmly secured together at all times and under all conditions of service. At the same time I have provided a crushing-head in which the mantle may be removed when worn out and replaced by a new one. I believe that I am the first to attain these important advantages. 50

I claim—

In a rock and ore breaker, a crushing-head comprising a core portion of relatively soft metal, said core portion having an inclined 60 outer surface, a mantle of relatively hard metal closely fitting the core portion, and an inwardly-projecting lug having an inclined face, said lug being located at the lower edge of the mantle and said core being provided 65 adjacent its lower edge with a vertical groove having inclined wedge portions for engaging the lug on the mantle.

GEORGE HENRY THURSTON.
